UNITED STATES PATENT OFFICE.

ERNEST L. ALLEN, OF ELROSA, MINNESOTA.

TICKET-HOLDER.

1,171,688.

Specification of Letters Patent. Patented Feb. 15, 1916.

Application filed May 5, 1915. Serial No. 26,102.

To all whom it may concern:

Be it known that I, ERNEST L. ALLEN, a citizen of the United States, residing at Elrosa, in the county of Stearns and State of Minnesota, have invented new and useful Improvements in Ticket-Holders, of which the following is a specification.

The present invention comprehends the provision of a combined register and ticket ejector primarily intended for use in connection with a receptacle for holding tickets such as employed in railroad ticket offices and like places, although the invention is susceptible to other analogous uses.

The primary object of the invention resides in the provision of a device of this character, designed to register each ticket as the latter is ejected from the receptacle, with a view of eliminating all figuring in determining the amount of sales at the end of each day's work, and positively assuring the correctness of its indications.

The nature and advantages of the invention will be better understood from the following description when taken in connection with the accompanying drawings, wherein like numerals of reference indicate similar parts in the several views and in which:—

Figure 1 is a side elevation of the device. Fig. 2 is a similar view with the casing removed showing the position of parts ready to eject a ticket from the receptacle. Fig. 3 is a similar view showing the normal position of parts and the manner of ejecting the ticket from the receptacle. Fig. 4 is a top plan view. Fig. 5 is a longitudinal sectional view taken on line $a-a$ of Fig. 4. Fig. 6 is a detail view of the yoke and ejector.

Referring more particularly to the drawings 5 indicates the receptacle for holding the ticket, and as shown in this particular instance the receptacle is of elongated substantially rectangular formation in cross section, having a longitudinally disposed slot 6 in the top wall thereof extending throughout its entire length, the top wall from a point an appreciable distance from the forward end of the receptacle being inclined 45 downwardly as at 7, the inclined wall terminating short to provide a discharge opening 8, while the receptacle is filled with tickets through an opening 9 in the opposite end thereof, the opening being closed by a suitable cover 10.

With a view of ejecting the tickets singly

from the receptacle, and registering the sale of each ticket I employ a device including spaced pairs of uprights 11 secured to the opposite side walls of the receptacle and projecting above the inclined portion thereof, and between each pair of uprights is journaled a shaft 12. Fixed upon the shafts 12 for rotation therewith are a pair of spools or rolls 13 and 14 respectively, upon which is wound a tape 15 having indicia thereon to register the sale of each ticket, the tape being adapted to be wound upon the roll 13 from the roll 14 step by step as the tickets are singly ejected from the receptacle in the manner to be presently described, the roll 14 being a spring operated roll to retain the tape taut as will be readily understood.

Loosely mounted upon the shaft supporting the roll 13 is a yoke 16 the arms of which project forwardly in advance of the roll 13, while the arms 17 forming a continuation of the arms of the yoke 16 normally extend downwardly terminating below the roll 13 and are connected by a cross piece 18, while projecting from the cross piece 19 connecting the arms of the yoke 16 is a handle 20 for operating the yoke member. Coil springs 21 terminally secured at one end to the side walls of the receptacle and having their opposite ends connected with the arms 17 of the yoke member operate to retain the member normally in the position shown in Fig. 3, at which time the spring pressed pawl 22 pivoted to the arms of the yoke 16 engages the teeth of a ratchet wheel 24 fixed upon the shaft adjacent one end of the roll 13, so that when the handle 20 is depressed imparting a rocking movement to the yoke 16, the roll 13 is rotated the required distance to wind the tape 15 thereupon from the roll 14 a predetermined distance, and upon release of the handle 20 the springs 21 operate to return the parts to normal position as clearly shown in Fig. 3. Pivoted upon one of the uprights 11 is a resilient pawl 25 adapted to engage with the teeth on the ratchet wheel 24 to prevent retrograde movement of the roll 13 when the pawl 22 is released during the return movement of the yoke to normal position.

Depending centrally from the cross piece 18 of the yoke is a relatively short stem 26 upon the free end of which is pivoted an ejector in the nature of a pointed finger 27 which as clearly shown in Fig. 3 is normally disposed below the roll 13 substantially in

parallelism with the inclined surface of the receptacle 5. When the handle 20 is depressed imparting a rocking movement to the yoke 16, the ejector is elevated riding in the slot 6 of the receptacle 5 until the position clearly shown in Fig. 2 is assumed, and upon release of said handle the ejector engaging the uppermost ticket within the receptacle ejects the ticket therefrom upon its return movement to normal position under action of the springs 21.

Manifestly by reason of the construction hereinabove described, when the handle 20 is depressed the tape 15 is caused to be wound upon the roll 13 from the roll 14 the required distance to register the sale of each ticket, and upon return movement of the handle to normal position the tickets are singly ejected from within the receptacle.

If desired an indicator may be employed in connection with my device comprising a stem 28 secured to the side walls of the receptacle and having a pointer overlying the tape 15.

The entire mechanism constituting the register and ejector is wholly inclosed by a suitable casing 29 with the exception of the handle 20 which projects through the casing, the latter having a sight glass 30 in the top wall thereof to permit the indicator to be viewed therethrough.

It is believed that from the foregoing description the nature and advantages of the invention will be readily apparent without

requiring a more extended explanation and therefore the same has been omitted. However I desire to have it understood that while I have shown and described the preferred embodiment of the invention I do not limit myself to the specific construction and arrangement of parts disclosed, as the same are merely illustrative and that various changes in this respect may be resorted to when desired as fall within the scope of the appended claim.

What is claimed is:—

The combination with a receptacle having a discharge opening, of a ticket ejector comprising a pair of spaced parallel members pivotally supported for rocking movement above said opening, cross pieces connecting said parallel members at both ends, a freely pivoted ejector associated with one of said cross pieces and normally disposed in inactive position, a casing inclosing said parts, a handle projecting from the other of said cross pieces through a slot in said casing and adapted when depressed to move said ejector to active position, means for automatically returning said parts to normal position upon release of said handle, and said ejector being operable during return movement.

In testimony whereof I affix my signature in presence of two witnesses.

ERNEST L. ALLEN.
